RAILWAY TIE PLATE

George Thompson Willard, St. Louis, Mo.

Application March 24, 1934, Serial No. 717,131

6 Claims. (Cl. 238—349)

This invention relates to railway tie plates.

The object of the invention is to produce a tie plate provided with means for resiliently holding the rail on the plate by exerting yielding pressure on the outer vertical faces of the rail base flange. Rail creeping is thus retarded or eliminated without rigidly connecting the rail and plate together. Rigid connection of the rail and plate is objectionable because of the tendency to lift the tie from its bed by the wave motion of the rail under load when the rail, plate and tie are rigidly connected together.

Tie plates embodying my invention may be rigidly fastened to the ties by means of screw spikes or bolts which reduce mechanical wear on the tie.

My novel connecting means for resiliently connecting the rail and plate exerts pressure in a horizontal direction against the rail base flange. It may also embody means for yieldingly bearing on the upper surface or both upper and lower surfaces of the rail base flange, for retarding or limiting the upward vertical movement of the rail relatively to the plate due to wave motion of the rail under load.

The connecting means for resiliently holding the rail on the plate is preferably put under tension by means of a rigid hold-down clip, a bolt, a screw spike or other means which may be adjustable as to height and pressure relatively to the resilient connection. Resilient connections may be used on one or both sides of the rail base.

The connecting means between the tie plate and the rail is movable vertically with the rail, but substantially confined against horizontal movement with the creeping of the rail by lugs or shoulders formed on the top surface of the tie plate adjacent to the rail base edges. These lugs or shoulders may be formed integrally with the plate in the rolling of the tie plate or during the finishing process.

The connecting means between the tie plate and the rail is movable vertically with the rail but holds the rail under downward pressure as well as horizontal pressure. This yielding connection between the tie plate and the rail may be used on either one side or both sides of the rail base flange. When the spring connection is used on one side of the rail base flange the opposite edge of the rail base flange will be in engagement either with a substantially vertical high shoulder or a shoulder that rises above and is turned over to overhang the rail base flange, but spaced therefrom to allow the free vertical movement of the rail wave motion under rolling loads.

In the drawings:

Fig. 1 is a plan view of a tie plate provided with rail engaging means embodying my invention.

Fig. 2 is a longitudinal, vertical sectional view taken on the line 2—2 of Fig. 1.

Fig. 3 is a transverse, vertical section taken on the line 3—3 of Fig. 2.

Fig. 4 is a plan view of a tie plate provided with modified rail engaging means embodying my invention.

Fig. 5 is a longitudinal, vertical section taken on the line 5—5 of Fig. 4.

Fig. 6 is a view similar to Figs. 1 and 4, showing other modifications of the invention.

Fig. 7 is a longitudinal, vertical section taken on the line 7—7 of Fig. 6.

Referring to that embodiment of my invention shown in Figs. 1 to 3, inclusive, the tie plate 10 comprises a rail seat 11, transversely extending rail abutting shoulders 12, 13, end surfaces 14, 15, and a tie bearing surface 16. The bottom 16 as shown is flat but obviously the plate bottom may be of any desired configuration. Holes 17 are provided for the reception of screw spikes or bolts for fastening the plate to the tie.

The rail base flange has vertical outer faces 18, 19, which abut the shoulders 12, 13, respectively.

For purposes of illustration, two forms of rail engaging means are shown in connection with the plate of Figs. 1 and 2. On the left hand side, the resilient arm 20 of spring metal is provided with a downwardly curved plate bearing end 21 arranged to seat in a transverse slot or recess 22 in the plate end 14, and at its opposite end is provided with a rail engaging portion 23. The part 23 exerts pressure, in a horizontal direction, against the rail base flange edge 18. Just above the part 23 is a rail-overhanging member 23' which is an integral part of the arm 20.

The arm 20 is apertured between its ends and a screw bolt 24 is adapted to extend upwardly through said aperture. The head 25 of the bolt 24 is adapted to enter a recess 26 formed in the plate. The recess 26 preferably communicates with the recess 22, forming a key-hole slot. The shape of the recess 22—26 is such that the head 25 may be inserted through an opening in the top of the plate, with the longitudinal edges of the head extending longitudinally of the plate. Then the bolt 24 is turned 90 degrees so that the longitudinal edges of the head 25 are transversely of the plate and the head is engaged beneath the shoulders 27 which extend toward each other.

and partially close said recess 26. The resilient arm 20 is placed over the bolt 24 and moved downwardly into the position shown in the drawings, and is held under tension by a nut 28 5 screwed down on the bolt 24.

The shoulder 12 is cut away to accommodate the arm 20 between the shoulder ends 29. When the parts have been assembled into the positions shown, and the arm 20 is under tension, the rail 10 engaging end 23 bears on the outer face 18 of the rail base flange, and retards or eliminates creeping of the rail. The overhanging member 28' retards vertical movement of the rail but the rail and plate connection is non-rigid and, therefore, the wave motion of the rail does not lift the rigidly connected plate and tie from the road bed.

Referring now to the form of connecting means shown at the right hand side of Figs. 1 and 2, 20 the resilient arm 30 has its plate bearing end 31 seated on the plate end 15, against a transverse shoulder 32. Its opposite end is split, forming a pair of rail engaging ends 33, and a rail-overhanging member 34 between the ends 33. The 25 recess 26 and the arm fastening bolt and nut 24 and 28 are identical with similarly designated parts heretofore described.

Referring to Figs. 4 and 5, for purposes of illustration two forms of rail and plate connecting 30 means are shown on one tie plate. At the left, the resilient arm 35 has a plate bearing end 36 seated on the plate end 14, against a shoulder 31. At its opposite end the arm forms a rail bearing member 38, terminating in a rail-overhanging 35 end 39. The arm 35 is apertured and a screw spike 40 extends through said arm aperture and a hole in the plate end 14, into the tie 41, holding the resilient arm down on the plate, under tension, and also fastening the plate to the tie.

40 At the right hand side of the Figures 4 and 5 the arm 42 has its plate bearing end 43 shaped to straddle the screw spike 40, and at its opposite end terminates in a rail bearing member 44. In this form I preferably use a clip 45 between the 45 head of the screw spike 40 and the arm 42. The clip is rectangular, as shown, and bears against the plate and shoulder 46 at its outer edge and on the arm 42 at its inner edge.

At the left hand side of Figs. 6 and 7 the 50 resilient arm 47 has a plate bearing end 48, seated against the shoulder 49, and on the opposite end the arm 47 is split, forming a pair of upturned, rail bearing surfaces 50, terminating in rail-overhanging ends 51. Between the two members 50-51 is a downturned member 52 extending into a punched slot 53 in the plate 10, with the end of the part 52 beneath the edge of the rail base flange. The arm 47 is held on the plate and under tension by the screw spike or bolt 40 heretofore described.

At the right hand side of Figs. 6 and 7 the 55 resilient arm 54 has its plate bearing end 55 shaped to straddle the screw spike 40, and at its 60 opposite end is bent to form a rail-overhanging member 56, and then bent downwardly to provide a rail flange bearing member 57 terminating in an end 58 located in a punched out slot 59 in the plate 10. The resilient arm is held under 65 tension on the plate by the screw spike 40.

The tie plate may be formed in a U or L section, 70 transversely; that is, with one or two depending flanges which have bearings against both sides or one side of the tie, thus reducing the strain 75 on the connection between the tie plate and the

tie caused by the tendency of the rail under traffic to creep.

The form of fastening device 24, 25, 28, shown in Figs. 1-3 may be substituted for the devices 40-45 of Figs. 4-7, inclusive, and vice versa. 5

Each of the spring metal arms 30 and 42, is provided with a rail engaging portion so located and formed as to normally exert non-slipping or biting bearing pressure in a horizontal direction only against a vertically disposed face of the rail 10 base flange when the arm is under tension; such tension being produced by the engagement of the plate bearing end of the arm with a rigid part of the plate and of the downward pressure of a clip, screw spike, bolt, or the like for fastening the 15 resilient arm to the plate. Thus the tie and plate may be rigidly connected together by screw spikes or bolts, and such connection will not be disturbed by the wave motion of the rail, non-rigidly held 20 on the plate.

The tie plate may be provided with means for temporarily establishing a rigid connection between the plate and rail as described in Willard United States Letters Patent No. 1,854,497.

Changes may be made in details of construction 25 without departing from the scope of my invention and I do not intend to be limited to the exact form shown and described, except as set forth in the appended claims.

I claim:—

1. A tie plate having a rail seat and provided with means for retarding rail creeping and for holding a rail centered on the seat while permitting limited movement in a vertical direction of the rail on the plate, said means comprising a 35 spring metal arm having a rail bearing portion in engagement with and biting into the outer vertical face of the rail base flange, shoulders upstanding from said plate adjacent said outer vertical face of the rail base flange on opposite 40 sides of said spring arm and preventing horizontal movement of the arm transversely of the plate, and fastening means connecting the arm to the plate and restraining means for said arm causing the arm to exert anti-creeping pressure through 45 said biting action solely in a horizontal direction against the outer vertical face of the rail base flange.

2. A tie plate having a rail seat and provided with means for retarding rail creeping and for holding a rail centered on the seat while permitting limited movement in a vertical direction of the rail on the plate, said means comprising a 50 spring metal arm having a rail bearing portion in engagement with and biting into the outer vertical face of the rail base flange, shoulders upstanding from said plate adjacent said outer vertical face of the rail base flange on opposite sides of said spring arm and preventing horizontal 55 movement of the arm transversely of the plate, and adjustable fastening means connecting the arm to the plate and restraining means for said arm causing the arm to exert controllable anti-creeping pressure through said biting action solely 60 in a horizontal direction against the outer vertical face of the rail base flange.

3. A tie plate having a rail seat and provided with means for retarding rail creeping and for holding a rail centered on the seat while permitting limited movement in a vertical direction of the rail on the plate, said means comprising a 65 spring metal arm having a rail bearing portion in engagement with and biting into the outer vertical face of the rail base flange, shoulders upstanding from said plate adjacent 70

- said outer vertical face of the rail base flange on opposite sides of said spring arm and preventing horizontal movement of the arm transversely of the plate, an abutment rising from the plate adjacent the face of the rail base flange opposite the face engaged by said spring arm, and fastening means connecting the arm to the plate and restraining means for said arm causing the arm to exert anti-creeping pressure through said biting action solely in a horizontal direction against the outer vertical face of the rail base flange. 4. A tie plate having a rail seat and provided with means for retarding rail creeping and for holding a rail centered on the seat while permitting limited movement in a vertical direction of the rail on the plate, said means comprising a spring metal arm slit longitudinally at one end and having a rail bearing portion in engagement with the outer vertical face of the rail base flange and a rail base overhanging portion normally out of contact with said rail base, shoulders upstanding from said plate adjacent said outer vertical face of the rail base flange on opposite sides of said spring arm and preventing horizontal movement of the arm transversely of the plate, and fastening means connecting the arm to the plate and restraining means for said arm causing the arm to exert anti-creeping pressure solely in a horizontal direction against the outer vertical face of the rail base flange. 5. A tie plate having a rail seat and provided with means for retarding rail creeping and for holding a rail centered on the seat while permitting limited movement in a vertical direction of the rail on the plate, said means comprising
- spring metal arms each having a rail bearing portion in engagement with and biting into the outer vertical faces of the rail base flange, shoulders upstanding from said plate adjacent said outer vertical faces of the rail base flange on opposite sides of said spring arms and preventing horizontal movement of the arms transversely of the plate, and fastening means connecting the arms to the plate and restraining means for said arm causing the arms to exert anti-creeping pressure through said biting action solely in a horizontal direction against the outer vertical faces of the rail base flange. 6. A tie plate having a rail seat and provided with means for retarding rail creeping and for holding a rail centered on the seat while permitting limited movement in a vertical direction of the rail on the plate, said means comprising a spring metal arm having a rail bearing portion in engagement with and biting into the outer vertical face of the rail base flange, shoulders upstanding from said plate adjacent said outer vertical face of the rail base flange on opposite sides of said spring arm and preventing horizontal movement of the arm transversely of the plate, a clip having bearing on said plate and said spring arm, and an adjustable fastening device bearing on the clip and connecting the arm to the plate and restraining means for said arm causing the arm to exert anti-creeping pressure through said biting action solely in a horizontal direction against the outer vertical face of the rail base flange.

GEORGE THOMPSON WILLARD. 35
